UNITED STATES PATENT OFFICE.

HERMAN NIELSEN, OF COPENHAGEN, DENMARK.

EXPLOSION-MOTOR WITH ROTATING CYLINDERS.

Specification of Letters Patent. Patented June 29, 1909.

No. 826,353.

Application filed October 7, 1907. Serial No. 396,195.

To all whom it may concern:

Be it known that I, HERMAN NIELSEN, mechanician, a citizen of the Kingdom of Denmark, residing at Faldevejens Passage 5 10, Copenhagen, Denmark, have invented a new and useful Explosion-Motor with Rotating Cylinders; and I do hereby declare the following to be a full, clear, and exact description of the same.

10 This invention relates to an explosion-motor, in which all the cylinders are arranged in the same plane through the shaft of the machine, with which shaft the cylinders rotate.

15 The drawing shows an example of carrying out the invention.

Figure 1 shows the machine seen from above, the cylinders being taken away. Fig. 2 is a lateral view of same, partially in section, Fig. 3 a view from the end, partially in section, Fig. 4 the cylinders seen from above, and Fig. 5 a detail.

The shaft of the machine marked 1 is hollow, the end to the left in Fig. 2 forming the inlet-canal 2 for lighting or other explosive gas, while a pipe 3 is placed in the other end, through which pipe the combustion-products escape. The shaft 1 is integral with four hollow pistons 4, arranged 25 in pairs at each side of the shaft, and all in the same plane. The pistons 4 are enclosed in cylinders 5 which are cast or formed in pairs which are so connected together by bolts 6 as to always preserve the same fixed 30 correlation. Each cylinder 5 is integral with a shaft 7 and around each such shaft a wheel 8 is rotatably mounted upon suitable ball-bearings. At each side the periphery of wheels 8 frictionally engage the rim of a 35 curved eccentric or cog-disk 10, preferably of the shape shown in the drawing, and one at each side of the machine-frame. In Figs. 2 and 3 of the drawing the upper cylinders are shown in their most advanced position, 40 while the piston is in the bottom in the lowest cylinders which are in their most retracted position. The cylinders are provided with external ribs of any desired form in order to increase the exposed surface, as 45 the machine is air-cooled. The hollow pistons 4, bear outside tightening rings 11, and communicate directly with the supply canal 2 in the shaft 1. In the interior of each piston is an outlet valve 12, for the products 50 of combustion, and within each valve 12 there is an inlet-valve 13, for gas. Each

valve 12 moves in a tube 14 placed in the corresponding piston 4 and has, at its upper end, a valve-head 15, tightening against its tube. The valve 12 is kept closed by a coiled spring 30 surrounding the tube 14 and pressing, at one end, against the head of this tube, while its other end presses against a pin 31, or the like, fitted through the valve 12. In each tube 14 there is provided a circular groove 16, (see especially Fig. 3) communicating with a canal 17 (Fig. 2) formed lengthwise of a piston 4 and communicating with the exhaust pipe 3 in the shaft 1; the two pistons shown at the extreme left hand side of the drawings communicate, however, with pipe 3 through an intermediate pipe 18, Figs. 1 and 5. In the interior of the valve 12 the valve 13 can slide, against the pull of the coil spring 19, which holds the head 15 or flange, 20, down against the valve 12, I prefer that each valve 12 shall be of the form shown in Fig. 3, that is provided with openings 21, for the passage of the gas. Each inlet-valve 13 is designed to be opened 80 by the suction due to the partial vacuum which is produced when the cylinders leave the pistons and the combustion-products are led out. The gas goes from the canal 2 through the hollow valves 12 and, upon 85 opening of valve 13, through the openings 21 and to the cylinder 5. The outlet-valves are moved by means of a cog-wheel 23 fixed to the machine-frame and having twice the number of teeth of the wheel 22 90 (Fig. 3). As the last named wheel is non-rotatably fixed to the machine-frame, the wheel 23 must, when the machine is working, rotate around its shaft 24, which is rotatable in bearings 25 fixed to the pistons 4. 95

On the shaft 24 are arranged four cams 26, so as to have each cam move a corresponding rod 27, which can actuate one arm of an angle-lever, the other arm 28 of which can lift the corresponding valve 12, Fig. 5. 100 For every two rotations of the shaft 1 the shaft 24 will rotate once, and consequently each of the valves 12 is opened once for every two rotations of the shaft 1, and, as regards the valves controlling two cylinders 105 disposed opposite each other, at every rotation of the shaft 1.

One eccentric 10 is provided with a terminal or bolt 32 to which electric current is conducted, the other end of the bolt gliding on a disk 33 which is placed on the shaft 1, and on which also glides one end of an

- 22
- arm 34, the other end of which is fixed to the shaft 24 and partakes of the planetary movement of the latter; at the other end of the shaft 24 the current goes through a smaller arm 35 conducting it to an insulated contact-piece 36 which is carried by the wheel 23 and partakes of the rotation thereof and will, upon each rotation, send the current through four contacts 38, in order one after another. Said contacts are provided, in proportion, to the wheel 23 on a non-rotating disk 37, and each contact communicates with a known igniting device, in each of the cylinders.
- 15 The foregoing description and drawings relate principally to a four cycle motor; but it is evident that the principle can be applied as well for a two cycle motor, upon effecting the necessary alterations in the arrangements serving to actuate the valves and control the igniting. Such form of motor can also be constructed, as that specified, with four cylinders or with two cylinders.
- 20 25 Having now described my invention, what I claim and desire to secure by Letters Patent is:
1. In an explosion motor, the combination of a shaft integral with the pistons, supply and exhaust pipes fastened in the center of said shaft, cylinders lying axially in the same plane as the axis of the shaft, and so connected that their open ends are always the same distance apart.
  2. In an explosion motor, a hollow shaft,
- 5 oppositely-disposed, hollow pistons, constituting continuations of and non-rotatably secured to said hollow shaft and containing valves for supplying charges of gas for ignition, and oppositely-disposed cylinders slidably fitting said pistons and connected in permanent correlation.
3. In an explosion motor, a hollow shaft, a hollow piston, constituting a continuation of and non-rotatably secured to said hollow shaft, an inlet valve within the hollow of the piston and an outlet channel formed in said piston, in combination with a cylinder slidably fitting the piston.
4. In an explosion engine, a hollow shaft having integral with itself pistons arranged on opposite sides of the shaft in pairs and with their axes in the same line, in combination with corresponding cylinders slidably fitting said pistons and having their axes in the plane of the axis of the shaft.
5. In an explosion motor, a hollow shaft, a hollow piston constituting a continuation of and non-rotatably secured to said hollow shaft and a pair of valves one contained within the other and both contained within the hollow piston, in combination with a cylinder slidably fitting the piston.
- In testimony whereof, I have signed my name to this specification in the presence of two subscribing witnesses.
- HERMAN NIELSEN.
